UNITED STATES PATENT OFFICE.

ALEXANDRE SENECA AND EDDY GIROUARD, OF ST. HYACINTHE, QUEBEC, CANADA.

GROOVING TOOL.

Application filed February 14, 1925. Serial No. 9,322.

To all whom it may concern:

Be it known that we, ALEXANDRE SENECA and EDDY GIROUARD, subjects of the King of Great Britain, residing at St. Hyacinthe, in the Province of Quebec, Canada, have invented certain new and useful Improvements in Grooving Tools; and we do hereby declare that the following is a full, clear, and exact description of the invention, such 10 as will enable others skilled in the art to which it appertains to make and use the same.

The present invention pertains to a novel tool designed to cut grooves in the aprons 15 or rolls of condenser or rubb machines used in the textile industry. These machines receive the fabric or stock after it passes through the carding machines in order to give it a firmer consistency.

Such a machine as already known in the art 20 consists of a pair of contacting rolls or endless aprons, one above the other, adapted to rotate and at the same time oscillate in opposite directions. The material coming from the carding machine is received 25 between the rolls or aprons. The latter are at present stamped or drilled with perforations or grooves for providing a rough surface to act on the stock. If the perforations or 30 grooves are stamped, they are soon filled by reason of the leather resuming its original condition under pressure. It is also found necessary at times to recut the grooves, even if they have been originally cut.

The object of the present invention is to 35 provide a tool for cutting the grooves originally if desired or recutting them if necessary after the machine has been in operation. The device consists of an arcuate member 40 adapted to engage the curved part of the roll or apron. The arcuate member or body carries a cutter and a pair of guide members so arranged as to tilt the body and cutter. Consequently, the movement of the roll or 45 apron against the cutter causes the formation of a spiral groove extending from one edge to the other.

The invention is fully disclosed in the following description and in the accompanying drawings, in which:

Figure 1 is an elevation of the device; Figure 2 is an elevation at right angles to Figure 1 showing the tool in operation; Figure 3 is a fragmentary longitudinal 55 section thereof;

Figure 4 is a section on the line 4—4 of Figure 3;

Figure 5 is a similar section to Figure 3, showing the guide member in a different position;

Figure 6 is a section on the line 6—6 of Figure 2;

Figure 7 is a section, partly in elevation, on the line 7—7 of Figure 6;

Figure 8 is a top plan view of the tool; 65

Figure 9 is a perspective view of one of the guide members;

Figure 10 is a perspective view of the cutter;

Figure 11 is a perspective view of a pair 70 of aprons grooved with the tool; and

Figure 12 is a front elevation thereof.

Reference to these views will now be made by use of like characters which are employed to designate corresponding parts throughout. 75

The tool comprises a back or body 1 of arcuate formation and extending substantially through 180 degrees. To each side of the body is attached a guide member 2 about half as long as the back and having 80 the same curvature. Each guide has a lip or edge 3 adapted to protrude within the circle defined by the inner edge of the body.

The guides are held to the body by means of a common pivot pin 4 passed through 85 these three parts at the upper end of the guides. Near its mid point each guide has a recess 5 in the inner face thereof for the purpose pointed out below. Below the recess is formed a slot 6 which receives a pin 90 7 passed through the body 1 and supported therein.

The lower end of the body is formed with a pair of spaced lugs 8 between which is pivoted a stem 9, the latter having a handle 95 or knob 10 at its lower end. Above the guide members, a strap 11 is passed through the body and carries a central knob 12.

The upper part of the body is split longitudinally as at 13 and transversely at one side as at 14. The cavity thus formed is normally filled by a block 15 held in place by a number of screws 16. The meeting walls of the split top and blocks are formed with complementary inclined recesses 16' 100 and still deeper inclined grooves 17. A V-shaped cutter 18 is inserted with its edges received in the grooves 17. The spaces 16 allow for the outlet of material cut by the edge of the cutter. 110

A stud 19 is passed through the top of the body 1, into the recesses 16, and is journaled on a nub 20 projecting from the inner wall of the block 15. The outer end of the 5 stud carries an operating knob 21, while the inner end is formed in the nature of a pinion 22. The latter meshes in grooves 23 cut transversely in the upper end of the cutter 18.

10 A spindle 24 is passed through the recesses 5 in the guide members and is journaled in the body 1 as shown in Figure 4. The spindle carries opposite cams 25 received in the two recesses. One end of the spindle is 15 provided with an operating knob 26.

In the use of the device, one of the edges 3 will be projected and the other retracted with reference to the body 1 due to the relation of the cams 25. The knob 26 is set to 20 give the desired extent of protrusion of the two edges. The tool is then applied to the apron or roll of a condenser or rubb machine. The form shown in Figure 11 is of 25 the apron type consisting of two pairs of spaced rollers 27, one pair above the other, and an apron 28 trained over each pair. The tool is placed against the apron adjacent one end of one of the rollers so that the cutter is uppermost and the guides beneath as shown in Figure 2. The knobs 10 and 12 are held by the operator, and by 30 means of them the tool is pressed tightly against the apron. The relation of the edges 3 as described above causes the tool to tilt slightly as a result of which the cutter is also tilted. During movement of the apron from the rotation of the rollers 27, the cutter will therefore form a spiral groove 29 extending from one edge of the apron to 35 the other. After the groove has been started, the protruding edge 3 will be received therein and the tool will thereby be guided transversely across the apron. The tool is then applied in the same manner to the remaining apron to form an oppositely inclined 40 groove 30 as shown in Figure 12. The straight arrows to Figures 11 and 12 indicate the opposite oscillation of the aprons during rotation in a manner already known 45 in the art.

50 While a specific embodiment of the invention has been illustrated and described, it is to be understood that various alterations in the details of construction may be

made without departing from the spirit of 55 the invention as indicated by the appended claims.

Having thus fully described the invention, what we claim as new and desire to protect by Letters Patent is:—

60 1. A tool of the character described comprising a body, a cutter carried by said body, a pair of guide members attached to said body, and lips extending from said guide members unequally beyond one of the 65 edges of said body.

2. A tool of the character described comprising a body, a groove cutter carried by said body, a pair of arcuate guide members attached to said body, and lips extending 70 from said guide members unequally beyond the inner circumference of said body.

3. A tool of the character described comprising a body, a cutter carried by said body, a pair of guide members attached to said body, and means for adjusting said guide members simultaneously in opposite 75 directions.

4. A tool of the character described comprising a body, a cutter carried by said body, a pair of arcuate guide members attached to said body, and means for adjusting said guide members simultaneously in opposite 80 directions.

5. A tool of the character described comprising a body, a cutter carried thereby, guide members pivoted to the sides of said body, lips extending from said guide members unequally beyond one of the edges of 85 said body, said guide members being formed with recesses, a spindle through said recesses and through the body, and opposite cams 90 mounted on said spindle and received in said recesses.

95 6. A tool of the character described comprising a body, a groove cutter carried thereby, arcuate guide members pivoted to the sides of said body, lips extending from said guide members unequally beyond one 100 of the edges of said body, said guide members being formed with recesses, a spindle through said recesses and through the body, and opposite cams mounted on said spindle and received in said recesses.

105 In witness whereof we have hereunto set our hands.

ALEXANDRE SENECAL.
EDDY GIROUARD.
